UNITED STATES PATENT OFFICE.

WILLIAM F. GRUPE, OF HUDSON HEIGHTS, NEW JERSEY, ASSIGNOR TO ENDLESS BELT CORPORATION, INC., A CORPORATION OF NEW YORK.

BELT-GUIDING MEANS.

1,391,184.

Specification of Letters Patent. Patented Sept. 20, 1921.

Application filed May 31, 1919. Serial No. 300,930.

To all whom it may concern:

Be it known that I, WILLIAM F. GRUPE, a citizen of the United States of America, residing at Hudson Heights, county of 5 Bergen, State of New Jersey, have invented certain new and useful Improvements in Belt-Guiding Means, of which the following is a specification.

This invention relates to guiding means 10 for belts. Heretofore guiding means have been provided for guiding a belt by frictional engagement with the edges of the belt, but such guiding means causes considerable wear of the edges of the belt, and materially reduces the effective life of the belt, 15 particularly for belts for cigarette making machines and the like.

In accordance with this invention, the guiding means comprises rotary members 20 constructed and arranged to engage the belt at spaced portions disposed remote from the edges of the belt whereby the extent of wear is reduced, and the belt effectively guided without contact with the edges.

25 In the most preferred form of the invention, the guiding means comprises spaced rotary members having their effective guiding faces arranged angularly to one another and constructed to cause the belt to be 30 curved for the regions of contact with the rotary members.

Further features and objects of the invention will be fully described in the following specification and the accompanying 35 drawings, in which—

Figure 1 is a detail perspective view of one form of the invention;

Fig. 2 is a front elevation of the same, partly in section, on a somewhat enlarged 40 scale;

Fig. 3 is an end elevation of Fig. 2; and

Fig. 4 is a detail perspective view of a modification; Fig. 5 is a partial end view of Fig. 4.

45 Referring to the drawings, the guiding means comprises a base 1, on which are mounted the angularly arranged, oppositely disposed rotary members 2, 3, carried by said base 1 by means of the axis pins 4. In 50 the embodiment shown, each rotary member 2, 3, is cylindrical, although the exterior face of the same may be varied as may be desired; in Fig. 4 I have shown a modification embodying curved roller faces 2^a, 3^a.

55 Preferably, each rotary member 2, 3, is

mounted on roller bearings 5, 6, disposed respectively at the bottom and at the top of the axis pin 4, and held in position by means of the cap 7, secured by means of a screw 8 to the axis pin 4.

The base 1 may be provided with the angular faces 9, 10 determining the angle of convergence of the rotary members 2, 3.

The base 1 is provided with a suitable slot 11 for the reception of a suitable bracket 12, 60 for carrying the base 1 from the body of a machine or like fixed support. Preferably, the base 1 is provided with suitable means for adjusting the position of the same relative to the bracket 12, and in the specific 65 form shown in the drawings, I have provided the adjusting nut 13 loosely mounted within the opening 14 and extending within the recess 11 and provided with the knurled head 15; its threaded portion 16 is received 70 within the threaded opening 17 of the bracket 12. After attainment of proper position of the base 1 relative to the bracket 12, the bracket 12 may be finally set by 75 means of the set screw 18 projecting through 80 a lateral side of the base 1 and extending into the recess 11 sufficiently to frictionally bind the bracket 12.

In the operation of my invention, the belt such as a belt 18^a of a cigarette making machine, is received between the converging 85 rotary members 2, 3, as indicated in Figs. 1 and 2, and 4, said rotary members 2, 3 being effectively spaced from one another to cause the belt 18 to be curved at its oppositely disposed interior portions 19, 20, whereby the regions of engagement of the respective rotary members 2, 3, with the belt 18^a is at a distance from the respective edges 21, 22 of the belt. Similarly, for the construction of Fig. 4, wherein the curved faces 2^a, 3^a perform their combined guiding function with a relatively lesser curving effect of the belt 1. Accordingly, the force required for guiding the belt 18^a and exerted 100 by means of the respective rotary members 2, 3, is distributed over a relatively large area of the belt, as compared with the edges proper 21, 22 with the belt 18^a, as obtains in heretofore proposed arrangements, and the 105 resultant of such forces exerted in the guiding of the belt is directed over portions of the belt which is formed of a relatively great number of warp and weft strands of threads.

In the modification shown in Fig. 4, the 110

axes of the guiding rollers are disposed at lesser angular relation, and may be substantially parallel, if desired, according to the curve or curvature of the roller faces and the effective spacing between the roller faces.

The spacing between the effective faces of the rollers is determined by the width of the belt.

If desired, one or both of the axis pins 4 10 may be mounted on a support plate adjustable relatively to the base 1. In Fig. 4 I have indicated the roller 3^a, having its pin 4, mounted on the plate 25 slidably mounted on the base 1 in the oppositely disposed 15 grooves 26, 27, the block 1 being hollowed out at 28, into which space 28 projects the nut 29 fixed to and depending from the plate 25, and receiving the threaded portion of the adjusting screw 30, provided with the 20 knurled head 31 whereby the spacing between the guide roller 3^a is regulatable with respect to the guide roller 2^a.

The invention is applicable for guiding belts employed for general use, but is particularly applicable for fabric belts, and is especially advantageous for fabric belts having a relatively larger number of warp threads for the portion of the belt disposed more or less central of the belt, such as is 25 disclosed in my copending application respectively entitled Woven fabric, Serial No. 213,627, filed Jan. 23, 1918, and Cigarette conveyer band, Serial No. 137,949, filed December 20, 1916.

35 It will be noted that the invention is self-adjustable, without regulating the special relation between the rollers 2, 3, for varying widths of belts within certain range of widths, the wider belts engaging the rollers over greater effective areas of contact than the narrow belts.

Whereas I have described my invention by reference to specific forms thereof, it will be understood that many changes and modifications may be made without departing 45 from the spirit of the invention, as defined by the appended claims.

I claim:

1. The combination of a substantially flat belt and means for diverting the path of travel of said belt at any given single location to provide for the travel of the belt in

flat position anteriorly and posteriorly of said given single location, said diverting means comprising a plurality of guiding members disposed oppositely one another and laterally of the belt and immediately adjacent said given single location, said guiding members having guiding faces extending at an angle to one another. 60

2. The combination of a substantially flat belt and means for diverting the path of travel of said belt at any given single location to provide for the travel of the belt in flat position anteriorly and posteriorly of 65 said given single location, said diverting means comprising a plurality of relatively movably mounted guiding members disposed oppositely one another and laterally of the belt and immediately adjacent said given 70 single location, said guiding members having guiding faces extending at an angle to one another.

3. The combination of a substantially flat belt and means for diverting the path of 75 travel of said belt at any given single location to provide for the travel of the belt in flat position anteriorly and posteriorly of said given single location, said diverting means comprising a pair of guiding members arranged oppositely to one another and laterally of the belt and immediately adjacent said given single location, said guiding members having guiding faces extending at 80 an angle to one another. 85

4. The combination of a substantially flat belt and means for diverting the path of travel of said belt at any given single location to provide for the travel of the belt in the flat position anteriorly and posteriorly 90 of said given single location, said diverting means comprising a pair of guiding members arranged oppositely to one another and laterally of the belt, anterior means for mounting said pair of guiding members adjacent said given single location, said guiding members having guiding faces extending at an angle to one another, and adjustable means for said mounting means for adjusting the positions of said guiding 100 members relative to said belt.

In testimony whereof I have signed this specification this 26th day of May, 1919.

WILLIAM F. GRUPE.
